UNITED STATES PATENT OFFICE.

JAMES JACKSON, OF HELENA, ALABAMA.

REVERSIBLE ROTARY ENGINE.

SPECIFICATION forming part of Letters Patent No. 624,814, dated May 9, 1899.

Application filed November 12, 1898. Serial No. 696,283. (No model.)

To all whom it may concern:

Be it known that I, JAMES JACKSON, a citizen of the United States, residing at Helena, in the county of Shelby and State of Alabama, have invented certain new and useful Improvements in Reversible Rotary Engines; and I do declare the following to be a full, clear, and exact description of the invention, such as will enable others skilled in the art to which it appertains to make and use the same.

My invention relates to improvements in reversible rotary steam-engines; and the object is to provide a simple, inexpensive, and efficient motor of this character.

To this end the invention consists in the construction, combination, and arrangement of the several parts of the same, as will be hereinafter more fully described, and particularly pointed out in the claim.

In the accompanying drawings the same reference characters indicate the same parts of the invention.

In said drawings, Figure 1 is a vertical longitudinal section of my improved reversible rotary steam-engine. Fig. 2 is an end elevation.

1 denotes the casing, 2 the steam-chest, and 3 the rotating drum, fixed on the shaft 4, journaled in suitable bearings fixed on the removable side plates of the casing. The drum 3 is formed with a continuous series of radial buckets 5 extending entirely around its periphery.

6 designates the upper exhaust-port, and 7 the lower exhaust-port, which also forms an exit for the water of condensation which may form in the casing while the engine is in operation.

8 8 8 denote the live-steam ports, when the steam is admitted to rotate the drum in the direction of the arrow, and 9 9 9 the corresponding live-steam ports, which are in use when the engine is revolving in the opposite direction.

10 denotes the slide or throttle valve, which

is provided with a stem extending through the steam-chest, and 13 denotes the steam-pipe leading direct to the boiler.

The operation is very simple, the starting, stopping, and reversing and the speed being all regulated and controlled by the single valve 10, which when moved to cover all the ports cuts off the steam from the drum and causes it to stop. If it is desired to start the drum in the direction of the arrow, the valve is moved to the right, which uncovers one or more of the ports 8, the ports 9 remaining closed, and, reversely, if it is desired to start the engine in the opposite direction the valve is moved to the left to close the ports 8 and open the ports 9, which admit steam to the opposite side of the drum, thereby causing it to rotate in the direction opposite to the arrow.

It will be understood that changes in the form, proportion, and the minor details of construction may be resorted to without departing from the spirit or sacrificing any of the advantages of this invention.

Having thus described my invention, what I claim, and desire to secure by Letters Patent, is—

The combination, in a reversible rotary steam-engine, of the casing or cylinder, 1, formed with the upper and lower exhaust-ports, 6 and 7, the drum, 3, mounted therein and formed with the radial buckets, 5 5, the steam-chest, 2, and the duplex series of diverging live-steam ports, 8 8 8 and 9 9 9, connecting the steam-chest and cylinder-casing, the slide-valve, 10, adapted to cover either series of live-steam ports independently, or both series simultaneously, substantially as shown and described.

In testimony whereof I have hereunto set my hand in presence of two subscribing witnesses.

JAMES JACKSON.

Witnesses:

HENRY MISON,

ALLEN MCCLELLAN.
